DESIGN FOR A PROGRESSIVE FLAME HARDENING BURNER

Albert L. Hartley, Cincinnati, Ohio, assignor to
The R. K. Le Blond Machine Tool Company,
Cincinnati, Ohio, a corporation of Delaware

Application April 22, 1941, Serial No. 100,568

Term of patent 14 years

To all whom it may concern:

Be it known that I, Albert L. Hartley, a citizen of the United States and a resident of Cincinnati, county of Hamilton, and State of Ohio, have invented a new, original, and ornamental Design for a Progressive Flame Hardening Burner, of which the following is a specification, reference being had to the accompanying drawing, forming a part thereof.

Figure I is a front elevational view of a progressive flame hardening burner embodying my new design.

Figure II is a left hand end elevational view of the progressive flame hardening burner shown in Figure I.

Figure III is a right hand end elevational view of the burner shown in Figure I.

Figure IV is a bottom view of the flame orifices portions of the burner shown in Figure I.

I claim:

The ornamental design for a progressive flame hardening burner, substantially as shown.

ALBERT L. HARTLEY.
